UNITED STATES PATENT OFFICE

2,602,553

CUSHION COUPLER FOR CARS

Henry Fort Flowers, Findlay, Ohio

Application May 18, 1948, Serial No. 27,671

12 Claims. (Cl. 213—75)

1

The invention relates to new and useful improvements in a mine car coupler and more particularly to a coupler which includes a draft gear for absorbing the shocks incident to coupling, accelerating and braking the cars in a train.

An object of the invention is to provide a coupler of the above type wherein the draft gear is enclosed so as to be protected from corrosion and to make possible effective lubrication of the wearing parts.

Another object of the invention is to provide a coupler which will allow individual cars in the train to be inverted in a rotary dumper without uncoupling.

Another object of the invention is to provide a coupler of the above type which may be permanently attached to a car and is provided with means for maintaining the same centered both vertically and horizontally to facilitate the entrance of the coupler paddle into the coupler pocket of a car to which it is to be attached.

Another object of the invention is to provide a cushion coupler of the above type and a coupler pocket therefor which permits cars to be automatically coupled while on a curved track having a radius of approximately 50 feet.

A further object of the invention is to provide a cushion coupler of the above type which may be manually swung on the coupling pin attachment therefor through an angle of substantially 45 degrees to facilitate the coupling of cars on a track of very sharp radius.

A still further object of the invention is to provide a car with a cushion coupler at one end thereof and a coupler pocket at the other end thereof which pocket is flush with the end of the car to facilitate the placing of the car next to a loading apparatus.

Another object of the invention is to provide a coupler having two telescoping elements with a compressing spring therebetween for absorbing the shock incident to coupling, accelerating and braking of the cars in a train wherein the elements make direct contact after the spring has been compressed to a predetermined degree to prevent overstraining of the compression spring.

A further object of the invention is to provide a coupler release which will stand unlocked and also lock or couple automatically when the compression shock of the bumping of the cars together is transmitted to the release rigging therefor.

These and other objects will in part be obvious and will in part be hereinafter more fully disclosed.

In the drawings which show by way of illustration one embodiment of the invention:

Figure 1 is a view in side elevation showing more or less diagrammatically two mine cars joined together by the improved cushion coupler;

Figure 2 is a plan view of the same;

2

Figure 3 is a vertical sectional view through the improved cushion coupler and also through the coupler pockets of two adjacent cars which have been joined by the coupler;

Figure 4 is a view partly in plan and partly in section of one of the improved couplers permanently attached to a car;

Figure 5 is a view partly in section and partly in plan on the line 5—5 of Figure 3;

Figure 6 is a view similar to Figure 5 but showing the coupler as swung to an angle of substantially 45 degrees to the longitudinal center of the car to facilitate coupling on a sharp curve;

Figure 7 is a sectional view on the line 7—7 of Figure 6 also showing the coupler paddle sectioned on the same line;

Figure 8 is a view in end elevation of a car with parts broken away and sectioned to show the improved coupler releasing rigging with the coupler pin in lowered position;

Figure 9 is a view partly in plan and partly in horizontal section showing the housing for the coupling releasing mechanism and also showing the housing for the operating shaft therefor;

Figure 10 is a vertical sectional view longitudinally of the car showing in full lines the coupling pin as lowered into operative position and in dotted lines said coupling pin raised;

Figure 11 is a view showing the paddle of the improved coupling as about to enter the coupler pocket of another car while said cars are positioned on a curved track of approximately 50 degrees curvature.

Figure 12 is a similar view showing the coupler as partially entering the part and contacting the inclined side wall thereof which will force the coupler to turn to bring the paddle at the outer end of the coupler into a position to receive the coupling pin;

Figure 13 is a similar view but showing the coupler in its final position for joining the two cars; and

Figure 14 is a front elevation of the coupling pocket at the right of Figure 3, showing a portion of the coupling paddle through which the coupling pin passes;

Figure 15 is a sectional view on the line 15, 15 of Figure 14; and

Figure 16 is a sectional view on the line 16, 16 of Figure 14.

In Figures 1 and 2 there is shown a mine car indicated at 1 which is joined to a mine car indicated at 2 by the improved coupling 3. This improved coupling 3 includes coupler paddles 4 and 5. The coupler paddle 4 is attached to an outer tubular element or sleeve 6. Said sleeve has welded thereto a head or end plate 7 and the coupler paddle 4 is secured to this head by welding. The coupler paddle 5 is attached to an inner tubular member or sleeve 8. Said sleeve is provided with an end plate 9 which is welded

thereto and the paddle is in turn welded to this end plate 9.

Between the sleeve 6 and the sleeve 8 is a compression spring 10. Located between the inner and outer sleeves 6 and 8 and at one end of the compression spring is an annular follower block 11. This follower block is free to move between the sleeves. When the coupling is under compression strain, the follower block 11 abuts against the end of the head 7. When the coupler is under tensile strain, the follower block 11 abuts against a loading stop 12 which is welded to the inner end of the sleeve 8. There is a follower block 13 at the other end of the compression spring which is likewise free to move between the sleeves 6 and 8. When the coupling is under tensile strain, the follower block 13 abuts against an annular abutment plate 14 welded to the outer sleeve 6 and when the coupling is under compression strain, the follower block 11 abuts against the end of the head 7. The head 7 is secured to the outer sleeve so as to close said sleeve and the chamber in which the follower blocks are located. Likewise the annular plate 14 and the loading stop 15, together with the follower block 13, close the other end of the chamber containing the compression spring. This provides an enclosed chamber not only for the compression spring but for all movable wearing parts within the coupler so that it is protected against corrosion and also makes possible effective lubrication.

Located within the inner sleeve 8 is a tubular member 16. This tubular member makes free telescoping connection with the sleeve 8. At the inner end of the tubular member 16 is a head 17 which is welded to the tubular member 16 and closes the inner end of said tubular member. Disposed within the head 9 attached to the sleeve 8 is an abutment plate 18 which has a central projecting stud 19 engaging a recess in the inner face of the head 9. Between this abutment plate 18 and the head 17 of the tubular member 16 is a relatively light spring 20. The chamber in which this light spring is located is a closed chamber and lubrication can be furnished said chamber through the oil fitting 21.

In Figure 3, a portion of a mine car to which the improved coupler is permanently attached is shown in section. The floor plate of the car is indicated at 22, and the end plate of the car at 23. Depending from the floor plate 22 is a vertically disposed plate 24 which forms the rear and side walls of a coupler pocket. This plate 24 is circular in cross section at the innermost portion thereof, as indicated at 25. A plate 26 is welded to the plate 24 and serves as a bottom plate for the coupler pocket. The coupler paddle 4 is provided with an opening 27 for the coupling pin which is indicated at 28 in Figure 3. The inner end of the coupler paddle is curved about the center of the opening in the paddle, as indicated at 29. The opening in the paddle is slightly larger in diameter than the section of the coupling pin located in said opening so that the paddle under compression will abut against the inner curved surface 25 of the coupler pocket. This opening for the coupling pin is of sufficient diameter to permit free movement of the coupler when the cars joined by the coupler are passing around curved sections of track.

Welded to the under side of the floor plate 22 is a collar 30. This collar and the opening through the floor plate are tapered so as to fairly snugly fit a tapered portion of the coupling pin 28. At the lower side of the coupler

pocket is a supporting bracket 31 for the coupler paddle 4. Between the bracket and the paddle is a rubber ring 32 which serves as a cushion support for the paddle. This bracket 31 is welded to the upper face of the bottom plate 26 of the coupler pocket. Said bracket has a tapered opening to receive the lower tapered portion of the coupling pin 28. Said bracket has a cut-away portion 33, thus providing spaced ends 34 and 35 which are placed in contact with the inner face 25 of the plate 24 at the rear of the pocket. Cooperating with this bracket 31 on which the paddle 4 rests is a forked supporting foot 36. Said supporting foot 36 has members 37, 37 at the inner end thereof which bear against shoulders 38, 38 on the bracket 31. The supporting foot is attached to a supporting stem 39. This supporting stem is threaded into the supporting foot and rigidly secured thereto by a nut 40. The supporting stem 39 passes through a bushing 41 lining an opening in the head 7, and at its inner end bears against the head plate 17 of the inner tubular member 16. The spring 20 normally holds the head plate 17 pressed against the end of the stem 39.

The weight of a cushion coupler normally tends to move the same downward on the connection of the blade 4 with the coupling pin 28. However, any downward movement of a coupler will shorten the distance between the plates 17 and the shoulders 38 and this would force the stem 39 inwardly into the head 7, moving the plate 17 away from the head 7 and compressing the spring. The spring, however, is pre-loaded so that there is sufficient compression on the spring 20 to operate through this stem and foot to hold the coupling in a horizontal position and it will also prevent the coupling from oscillating up and down. If the coupling is moved a slight distance away from the center, then one of the members 37 on the foot 36 will move away from its shoulder and the distance between the other shoulder and the plate where contacted by the stem 39 will be shortened and again the spring 45 which is pre-loaded will move the coupling back to centered position. Thus it is that the stem 39 and the foot operating through the spring 20 will hold the coupling when disconnected from a car in a substantially horizontal position and in a centered position so that it will readily enter the pocket of the car to which it is to be attached.

Under normal conditions on a straight track the coupler will be centered both vertically and horizontally so that it will readily enter the coupling pocket of the car to which it is to be attached. During transit, the coupler is free to swing on the coupling pins when passing around curves.

The coupler pocket of the car to which the coupler is to be attached is similar in construction to the coupler pocket to which the coupler is permanently connected. At the right in Figure 3 is shown a portion of a car to which the coupler has been attached.

The floor plate of the car is indicated at 42 at the right of Figure 3. Depending from this floor plate 42 is a vertically disposed plate 43 which forms the rear and side walls of the coupling pocket. This plate is circular in cross section at the innermost portion thereof and is shaped similar to the plate 24 of the coupling at the other end of the car. Attached to this depending plate 43 is a plate 44 which is welded to the plate 43 and serves as a bottom plate for

the coupling pocket. Secured to the upper face of the bottom plate 44 is a supporting bracket 45 having forked ends similar to the forked ends of the bracket 31 in the coupling pocket at the other end of the car. This bracket 45 extends in front of the coupling as well as in the rear and there is an opening through the bracket for the coupling pin, which opening is tapered. The structure of this bracket and coupling opening is very similar to that of the bracket 31 as shown at the left in Figure 3. Disposed in the coupling pocket is an inclined plate 48. This inclined plate 48 is cut away in the central portion to receive the upper front portion of the bracket 45. The bracket 45 is in a sense recessed to receive the upper central portion of the plate 48. There are two rectangular blocks 49^a welded to the plate 48. Bolts 49, 49 extend through the bottom plate 44 of the coupling pocket and are threaded into the blocks 49^a respectively. These bolts serve to hold the plate in place and the purpose of the plate is to direct the coupling upwardly over the bracket 45 into position to receive the coupling pin. When the plate wears it can be removed and replaced by removing the bolts 49.

Attached to the bracket 45 is a directing plate 48. Said plate is secured to the bracket by means of a bolt 49. This plate can be removed and a new plate substituted therefor in case of wear. The purpose of the plate is to direct the coupler paddle 5 into proper vertical position in the coupler pocket. The side walls of the rear plate 43 are inclined outwardly away from each other and this serves as a means for centering the paddle 5 so as to bring the opening 46 in the paddle into alignment with the openings in the coupler pocket so that the coupler pin will pass through the opening in the paddle.

The floor plate 42 is provided with a collar 50 on the under side thereof and the opening through the floor plate and collar are tapered to fit the tapered portion of the coupling pin 47. The bracket 45 also has a tapered opening which fits a tapered portion at the lower end of the coupling pin. The pocket for the coupling paddle, as noted, has a wide gathering opening which guides the paddle into the pocket when coupling on curves.

Associated with the coupling pin 47 is an operating mechanism for lifting and lowering the coupling pin. Extending upwardly from the floor plate is a cylindrical guide member 51 which guides the coupling pin when it is lifted from the coupling pocket. A housing 52 mounted on the inner wall of the car body contains a coupler lifting device which includes a link 53 pivotally connected to the coupling pin 47. Said link at its upper end is connected to a crank pin 54 on the end of a crank arm 55 carried by a shaft 60. This shaft is mounted in a supporting sleeve 61 and extends into the housing and the crank arm is mounted on the inner end of the shaft. The outer end of the shaft is provided with an operating handle 62. This operating handle is so positioned that when the coupling pin is lowered, the handle is in lowered position, as shown in Figure 8. The shaft 60 is so disposed that it lies in a vertical line passing in rear of the center of the coupling pin. When the coupling pin is lowered, the connection of the crank arm to the link 53 passes a dead center line through the axis of the shaft and the connection to the coupling and any tendency of the coupling to work upward would tend to turn

the crank arm in a counterclockwise direction and this would bring the handle against the end wall of the car, which would limit any lifting movement of the coupling. Therefore, the coupling may be said to be automatically locked in coupling position. When the crank handle is turned so as to raise the coupling, the handle will then extend upwardly from the shaft and again the crank arm will be turned past dead center so that the coupling pin will be held raised, that is, locked in raised position.

When two cars are coupled together, the abutment shock will cause the crank arm to move forward and drop, thus releasing the coupling pin so that it will fall into place in the openings in the pocket and the opening in the paddle so that the cars are automatically coupled. This coupling releasing rigging therefor serves not only as a means whereby the coupling pin may be manually withdrawn, but it also locks the coupling pin in place when the cars are coupled so that it cannot work loose. It also locks the coupling pin in raised position so that it may be released by the shock incident to the coupling of the cars so that it will fall into engagement with the coupling paddle.

In Figures 11-13, there is illustrated an automatic coupling of cars on a track having a radius of approximately 50 feet. In Figure 11, the coupler is shown in its centered position and as the cars approach each other, it will enter the pocket of the car to which it is to be attached. As shown in Figure 12, the coupler contacts the tapered wall of the pocket and moves toward the center of the same, swinging on its own coupling pin. In Figure 13, the coupler is shown as swung on its own coupling pin and moved through contact with the tapered wall to a position where a coupling pin may be readily dropped into the opening in the paddle at the outer end of the cushion coupler.

It is noted that normally the end members are shaped so that they contact with the shoulders 38 at the lower portion J thereof. The centering spring pressure transmitted to the head 17 and stem 39 would lift the coupler considerably above the horizontal plane except for the transfer of the pressure from the lower portion of the member 37 to the upper portion K thereof.

Referring again to Figure 3, it will be noted that the inner sleeve 8 when moved inwardly to compress the spring 10 will after a predetermined extent of movement contact with the head 17 and this will prevent any further telescoping movement of the sleeves 6 and 8. This contact of the inner sleeve with the head of the outer sleeve occurs before the draft spring 19 can be compressed solid, thus the sleeve 8 and not the draft spring is required to carry the shock of the most severe buffing forces at the time two cars are coupled together. This inward movement of the sleeve 8 will also compress the spring 20 so that said spring assists the draft spring 10 when the coupler is subjected to coupling forces in compression or buff. This spring 20 serves also to take up any slack or free play in the longitudinal direction between the outer sleeve 6 and the inner sleeve 8. This spring 20 also performs a third function of maintaining the coupler and paddle 5 centered both vertically and horizontally.

The compression spring 10 is placed under the desired compression load before the load stops 75 12 and 15 are finally placed. This compression

spring which operates when the sleeves are moved inwardly relative to each other or outwardly relative to each other provides a double acting spring draft gear to absorb the shock of coupling, accelerating and braking the cars in a train.

The sleeve 8 is free to rotate about the longitudinal axis of the coupling in the sleeve 6. The abutment plate 18 pivots at the center of the head 9 of the inner sleeve 8. This permits the inner sleeve to rotate without in any way disturbing its connection to the outer sleeve and the inner tubular member 16 and the springs in the coupler. Referring to Figure 3, when the car 1, illustrated in part at the left of the figure, is rotated, all parts of the cushion coupler except the inner sleeve and its associated panel 5 rotate. When the car 2, illustrated at the right of Figure 3, is rotated only the inner sleeve and its associated paddle rotate, all other parts, including both springs remain stationary. Therefore, one or more cars may be placed in a rotary dumper and inverted without uncoupling the cars from the train.

In the use of the improved cushion coupler a specially constructed pocket is formed in one end of the car to which the coupler is permanently attached. In the other end of the car is a specially formed coupler pocket to receive the outer free end of the cushion coupler. These pockets have been described in detail above and the manner of coupling the cars. The pocket which receives the coupler is flush with the outer end of the car and does not project therefrom. This is very helpful in the loading of the car.

From the above, it will be noted that each car is equipped with the improved coupler at one end thereof and the built-in coupler pin releasing mechanism as well as a built-in pocket to receive the coupler blade of a car to be joined thereto. Therefore, the car cannot be turned around end for end without all cars being turned around. There are, however, many advantages from this improved coupler which is permanently attached to one end of the car, and the built-in construction for the other end of the car which permits it to be placed very close to a loader.

It is obvious that many changes may be made in the details of construction without departing from the spirit of the invention as set forth in the appended claims.

I claim:

1. A coupler for cars comprising an outer sleeve and an inner sleeve having sliding telescoping connection therewith, said sleeves being radially spaced from each other, a compression spring disposed between said sleeves, devices carried by said sleeves whereby both inward and outward movement of said sleeves relative to each other will place said spring under compression, a coupler paddle permanently secured to said outer sleeve and a coupler paddle permanently secured to said inner sleeve each coupler paddle being attached to the respective cars to be connected by a coupling pin permitting free swinging movement of the coupler relative to the cars when the cars are passing along curved sections of track.

2. A coupler for cars comprising an outer sleeve and an inner sleeve having sliding telescoping connection therewith, said sleeves being radially spaced from each other, a compression spring disposed between said sleeves, loading stops carried on the outer face of said inner

5 sleeve disposed adjacent the outer ends thereof, abutment members at the inner face of said outer sleeve, one of said loading stops cooperating with an opposed abutment member for compressing the spring when the sleeves are moved in one direction relative to each other and the other loading stop cooperating with its opposed abutment member for compressing the spring when the sleeves are moved in the opposite direction relative to each other, a coupler paddle permanently secured to the outer sleeve and a coupler paddle permanently secured to said inner sleeve each coupler paddle being attached to the respective cars to be connected by a coupling pin permitting free swinging movement of the coupler relative to the cars when the cars are passing along curved sections of track.

3. A coupler for cars comprising an outer sleeve and an inner sleeve having sliding telescoping connection therewith, said sleeves being radially spaced from each other, a compression spring disposed between said sleeves, devices carried by said sleeves whereby both inward and outward movement of said sleeves relative to each other will place said spring under compression, a coupler paddle permanently secured to the said outer sleeve and a coupler paddle permanently secured to said inner sleeve, said inner and outer sleeves being rotatable relative to each other whereby one or more cars in a train joined by said couplers can be inverted for dumping without uncoupling from the remaining cars.

4. A coupler for cars comprising an outer sleeve and an inner sleeve having sliding telescoping connection therewith, said sleeves being radially spaced from each other, a compression spring disposed between said sleeves, devices carried by said sleeves whereby both inward and outward movement of said sleeves relative to each other will place said spring under compression, a coupling paddle permanently secured to the said outer sleeve and a coupler paddle permanently secured to said inner sleeve, said outer sleeve having a closure head to which said coupler paddle is secured, and said inner sleeve having a length so as to contact with said head under severe coupling shock to prevent overstraining said compression spring.

5. A coupler for cars comprising an outer sleeve and an inner sleeve having sliding telescoping connection therewith, said sleeves being radially spaced from each other, a compression spring disposed between said sleeves, devices carried by said sleeves whereby both inward and outward movement of said sleeves relative to each other will place said spring under compression, a coupling paddle permanently secured to the said outer sleeve and a coupler paddle permanently secured to said inner sleeve, a closure head for the outer sleeve, a tubular member within said inner sleeve and having a free telescoping fit therewith, a closure plate at the inner end of said tubular member, a closure plate at the outer end of said inner sleeve, a second compression spring in said tubular member and inner sleeve adapted to be put under compression when the inner sleeve is moved into the outer sleeve of the coupling for assisting said first named compression spring in absorbing the shock of coupling or braking.

6. The combination of a car having a coupler pocket, a coupler having a coupler paddle extending into said pocket, a coupler pin adapted

to pass through an opening in the coupler paddle for securing the coupler to said car, said opening being dimensioned so that the paddle will contact the coupler pocket under compression shock, said coupler including an outer sleeve having a closure head to which said coupler paddle is permanently attached and an inner sleeve having sliding telescoping connection with said outer sleeve, said sleeves being radially spaced from each other, a compression spring disposed between said sleeves, devices carried by said sleeves whereby both inward and outward movement of said sleeves relative to each other will place said spring under compression, and a coupler paddle secured to said inner sleeve and adapted to be connected to a second car.

7. The combination of a car having a coupler pocket, a coupler having a coupler paddle extending into said pocket, a coupler pin adapted to pass through an opening in the coupler paddle for securing the coupler to said car, said opening being dimensioned so that the paddle will contact the coupler pocket under compression shock, said coupler including an outer sleeve having a closure head to which said coupler paddle is permanently attached and an inner sleeve having sliding telescoping connection with said outer sleeve, said sleeves being radially spaced from each other, a compression spring disposed between said sleeves, devices carried by said sleeves whereby both inward and outward movement of said sleeves relative to each other will place said spring under compression, and a coupler paddle secured to said inner sleeve and adapted to be connected to a second car, a tubular member located within said inner sleeve, said tubular member having a closure plate at the inner end thereof, a spring bearing against said closure plate and normally holding the closure plate in contact with the closure head of said outer sleeve, a bracket fixed within the coupler pocket, a supporting foot for the coupler having the inner end thereof forked and adapted to engage lugs on said bracket, a stem attached to said supporting foot and extending through said head and bearing against the closure plate of said inner tubular member whereby said spring operating through said stem and bracket will center said coupler vertically and horizontally relative to the coupler pocket to which it is attached.

8. A mine car having a coupler pocket beneath each end thereof, said coupler pockets having top and bottom walls and side walls which taper outwardly away from each other, a coupling pin associated with one of said coupler pockets and a cushion coupler fastened to the car permanently by said coupling pin, a bracket disposed within said coupler pocket and rigidly attached thereto, devices associated with the coupler and adapted to engage the bracket, a compression spring within the coupler and cooperating through said devices and the bracket in the coupler pocket for holding said coupler horizontal and in centered position relative to the car when uncoupled from another car.

9. A mine car having a coupler pocket beneath each end thereof, said coupler pockets having top and bottom walls and side walls which taper outwardly away from each other, a coupling pin associated with one of said coupler pockets and a cushion coupler fastened to the car permanently by said coupling pin, a bracket disposed within said coupler pocket and rigidly attached thereto,

a foot associated with said coupler adapted to engage said bracket, said foot having a stem projecting into the coupler housing, a compression spring bearing against the stem and operating through said foot for holding said coupler horizontal and in centered position relative to the car when uncoupled from another car.

10. A mine car having a coupler pocket beneath each end thereof, said coupler pockets having top and bottom walls and side walls which taper outwardly away from each other, a coupling pin associated with one of said coupler pockets and a cushion coupler fastened to the car permanently by said coupling pin, a bracket disposed within said coupler pocket and rigidly attached thereto, a foot associated with said coupler and having members adapted to engage shoulders on said bracket, said foot having a stem projecting through the head of the coupler housing, a sleeve within the coupler housing having a plate adapted to engage the end of said stem, a spring within said sleeve, and means for holding the spring under compression whereby said foot bearing against the bracket will hold the coupler horizontal and in centered position relative to the car when uncoupled from another car.

11. A mine car having a coupler pocket beneath each end thereof, said coupler pockets having top and bottom walls and side walls which taper outwardly away from each other, a coupling pin associated with one of said coupler pockets and a cushion coupler fastened to the car permanently by said coupling pin, a bracket disposed within said coupler pocket and rigidly attached thereto, a foot associated with said coupler and having members adapted to engage shoulders on said bracket, said foot having a stem projecting through the head of the coupler housing, a compression spring within the coupler housing and operating through said stem whereby said bracket will hold the coupler horizontal and in centered position relative to the car when uncoupled from another car, the coupling pocket at the other end of the car having therein a supporting bracket rigidly attached to the pocket, said bracket having an upwardly inclined face adapted to direct the blade of a coupling member into position for coupling.

12. A rail car having a coupler pocket at each end thereof, said coupler pockets having top and bottom walls and side walls which taper outwardly from each other, a coupling pin associated with one of said coupler pockets and a cushion coupler fastened to the car permanently by said coupling pin, a bracket associated with said coupler pocket, a foot associated with said coupler adapted to engage said bracket, and yieldable means operating through said foot and bracket for holding said coupler horizontal and in centered position relative to the car when uncoupled from another car.
